(57) **CLAIM**

The ornamental design for a medication timing cap add-on to pharmacy vials as shown and described.

DESCRIPTION

FIG. 1 is a front view of a medication timing cap add-on to pharmacy vials, showing our new design.

FIG. 2 is a rear view of the claimed design.

FIG. 3 is a left side view of the claimed design.

FIG. 4 is a right side view of the claimed design.

FIG. 5 is a top view of the claimed design.

FIG. 6 is a bottom view of the claimed design; and,

FIG. 7 is a perspective view of the claimed design.

The broken lines of the drawing represent environmental matter forming no part of the claimed design.
